UNITED STATES PATENT OFFICE.

WINFRED MUDGE BROOKS, OF EAST ORANGE, NEW JERSEY.

BAG-SEAL.

1,126,376.

Specification of Letters Patent.

Patented Jan. 26, 1915.

Application filed October 22, 1914. Serial No. 368,024.

To all whom it may concern:

Be it known that I, WINFRED MUDGE BROOKS, a citizen of the United States of America, and a resident of East Orange, in the State of New Jersey, have invented a new and useful Improvement in Bag-Seals, of which the following is a specification.

This invention relates to means for securely fastening and sealing the necks of bags of textile fabric containing gold or silver coin or other valuables, or articles of merchandise, so as to insure the detection of any tampering therewith, and thus to prevent the abstraction of the contents.

The present improvement is primarily additional to Edward J. Brooks' improvement in bag seals, patented April 25, 1911, by United States Patent No. 990,630; that 20 is to say—the improved bag seal preferably has, in combination, a loop-forming cord adapted to embrace the neck of a bag, and a compressible lead seal part having threading holes through which the ends of the 25 cord protrude sufficiently to be pulled to tighten the cord around the bag neck; said seal part being further constructed with projections on one side adapted to interact with recesses in the face of one of the dies 30 of a seal press to resist the pulling strain and prevent the displacement of the seal part between said dies, as set forth in said patent; also, preferably, a central threading hole through which the two ends of the 35 cord protrude and side holes parallel with said central hole to provide for a double loop of the cord as shown in said patent.

The present invention consists in a novel metallic third element combined with such 40 loop-forming cord and apertured seal part, the latter being made with or without said die-engaging projections and side holes, as hereinafter particularly described and claimed.

45 The leading objects of this invention are to add to the security of the seal by a pinning device penetrating the neck of the bag from side to side so as to permanently pin its folds together at the sealing operation 50 and so as to prevent unpinning the bag neck without destroying one or both of the metallic members of the seal; and to facilitate inspecting the fastened seal from time to time to make sure that it has not been 55 tampered with.

Other objects will be set forth in the general description which follows.

A sheet of drawings accompanies this specification, as part thereof.

Figure 1 is a perspective view of the wire 60 member of said third element of the improved bag seal; Fig. 2 is a perspective view of the same provided with its pushing and pulling knob; Figs. 3 and 4 are perspective views of the main seal part showing, 65 its respective sides; Fig. 5 is a sectional view of said main seal part threaded with the loop-forming cord, preparatory to use; Fig. 6 is a like view of the improved seal, with the cord tightened and said third element inserted, ready for the seal press; and Fig. 7 is a side view of the neck of a bag provided with a press-fastened seal of the improved construction.

The improved press fastenable seal is 70 composed of a neck pinning element *a*, a main seal part *b*, and a loop-forming cord *c*. Said neck-pinning element is in turn composed of two members, 1 and 2, the first of which is a piece of moderately hard wire, 75 Fig. 1, preferably iron, having its heel end provided with a crimp, 3, and its other end cut obliquely or otherwise pointed. Upon the crimped end of this wire said member 2, which is a pushing, pulling and loop 80 engaging knob, preferably and conveniently of lead, is cast fast. A flat thumb-engaging end 4 facilitates pushing the wire endwise through the folds of a bag neck, and conveniently roughened by indicating characters, preferably forming the word "Pull" 85 as shown to indicate its use for testing the fastened seal.

The seal part *b* is a compressible casting 90 of lead having a double-width central threading hole, 5, side holes, 6, 7, parallel therewith, and one or more transverse projections, 8, 9, Fig. 3, on one side to interlock with a correspondingly recessed bed die in the seal press as displacement preventing 95 means.

The cord *c* is preferably a hard twine of sufficient strength, and is preliminarily threaded through the main seal part *b*, as shown in Fig. 5.

The pinning element *a* is first applied by thrusting it through the folds of the bag's neck; the loose loops of the cord *c* are then passed over the neck and adjusted beneath the knob 2 as they are tightened by pulling 110

on the protruding ends of the cord. At the same time, as the main seal part *b* is drawn against the bag neck, the protruding end of the wire 1 is made to enter and pass through the central threading hole 5 between the two cord ends. A seal press is now applied in customary manner, the dies being first lightly closed on the seal part *b*, so as to cause said displacement preventing projections 8, 9 to interlock with the bed die, whereby the seal part is held in place while the cord receives a final tightening pull, and the pinning element *a* is pushed home. The dies are then fully closed so as to solidify the seal part upon the cord and wire and to impart to the latter an effective withdrawal-resisting bend, 10, Fig. 7.

Both ends of the pinning element *a* are conveniently exposed, so that it can be seen whether the wire 1 effectively penetrates the folds of the neck of the bag; and a pull on the knob 2 quickly determines whether the seal has been securely press-fastened or has been tampered with by cutting the wire between the bag neck and the seal part *b*.

The knob 2 also engages the tightened loops of the cord, and prevents slipping them on the neck of the bag in attempts to unfasten the seal.

The compressible seal part *b* may obviously be of different forms, as set forth for example in said Patent No. 960,630; and other like modifications will suggest themselves to those skilled in the art.

Having thus described said improvement, I claim as my invention, and desire to patent under this specification:

1. In a press-fastenable bag seal, a neck pinning element composed of a penetrating wire having a pointed end adapted to be thrust through the folds of the neck of a bag and a pushing and pulling knob at its other end, in combination with a compressible seal part having threading holes, and a loop-forming cord threaded through said seal part and adapted to embrace the neck of the bag and to engage with said knob as part of the fastened seal, substantially as hereinbefore specified.

WINFRED MUDGE BROOKS

ROSSLYN JAMOUNEAU.

the bag by its loops, the pointed end of the wire of said neck-pinning element being adapted to extend through the bag neck and to be press-fastened within said seal part, and its knob to engage the tightened cord loops.

2. In combination with a loop-forming cord and a compressible seal part, the latter having means including a central threading hole to engage said cord—a neck pinning element composed of a wire adapted to penetrate the neck of a bag, and to extend through said seal part within said central hole, and a pushing, pulling and loop-engaging knob fast on the heel end of said wire.

3. In combination with a loop-forming cord and a compressible seal part, the latter having means including a central threading hole to engage said cord—a neck pinning element composed of a wire adapted to penetrate the neck of a bag, and to extend through said seal part within said central hole, and crimped at its heel end, and a pushing, pulling and loop-engaging knob of lead cast fast on said crimped end.

4. The combination, in a press-fastenable bag seal, of a neck-pinning element composed of a penetrating wire and a knob adapted to be pushed and pulled by thumb and fingers, a compressible seal part having threading means including a central through hole adapted to be penetrated by the protruding point end of said wire, and means for preventing the displacement of said seal part when loosely held between the dies of the seal press by pushing home said neck-pinning element, and a loop-forming cord threaded through said seal part and adapted to embrace the neck of the bag and to engage with said knob as part of the fastened seal, substantially as hereinbefore specified.
